CONVEYER SYSTEM

Moses E. Cronemiller, Bellwood, Pa.

Application May 23, 1947, Serial No. 750,101

5 Claims. (Cl. 212—79)

1

This invention relates to a conveyor system. Farmers have a considerable amount of material to be carried from one place to another. Particularly, there is considerable labor attached to transporting feed to animals in the barn.

It is a principal object of this invention to provide a conveyor system that will operate on an overhead track to carry feed to the various stalls.

Other objects will appear to those skilled in the art from a reading of the following specification. The accompanying drawings illustrate a preferred embodiment of the invention, and it is understood that modifications may be made therein without departing from the spirit of the invention as hereinafter claimed.

Figure 1 represents a schematic view, not in proper proportion, of a conveyor system constructed in accordance with the principles of the invention.

Figure 2 is an elevation of a portion of the conveyor, showing the manual means for moving the material, taken along the line 2—2 of Figure 1.

Figure 3 is a horizontal section taken along the line 3—3 of Figure 1.

Figure 4 is a front view of the bucket or carrier in tipped or opening position.

Figure 5 is a side elevation of the bucket or carrier in closed position, taken from the right of Figure 4.

The barn or other enclosure is represented in the drawings as having two walls 11 and 12. An overhead track 13, which may comprise a rail or a rod, is fastened from wall 11 to the other wall 12. This track 13 is adapted to carry the bogie 14 of a single bucket or carrier 15. The cable 20 is fastened at one end 21 to the bogie 14, and after passing around the various pulleys and other instrumentalities to be described more fully hereinafter, is attached at the other end 22 to the bucket 15.

As indicated in Figure 1, the cable 20 leads from the bogie 14 around a pulley 26 on the wall 12, back to a pulley 27 on the wall 11, down around a manual pulley 30, over a pulley 31, over an idler pulley 32 on the bogie 14, and back to the bucket 15. If desired, the bogie 14 may comprise a pair of idler pulleys 36 and 37, and the wall 11 may also include idler pulleys 38 and 39. The cable 20 is so designed that it has a minimum of slack. It will be apparent, therefore, that since the distances between the terminal pulleys 30 and 27 and 26 are fixed, tension on the cable 20 anywhere

2

along its length will act to move the bucket 15 in one direction or the other.

The manual pulley 30 supports a crank 40 by which the pulley may be rotated. Clockwise rotation of the crank 40, from the position indicated in Figure 1 of the drawings, will pull the bucket 15 to the left, and rotation of the crank 40 in the opposite direction will pull the bucket 15 to the right.

10 Additional pulleys, such as 43 and 44, may be provided to reduce friction of the cable 20.

The pulley 31 is mounted at the upper end of a vertical rod 50, which is adapted to slide vertically in a horizontal bracket 51 supported on 15 the wall 11. The lower end of the rod 50 is pivoted to an arm 52, which itself is pivoted to the wall 11. The arm 52 is linked to a foot pedal 54, likewise pivoted to wall 11, by a link 55. It is obvious, therefore, that the arm 52 and the 20 foot pedal 54 will have substantially parallel movement about their respective pivots on the wall 11.

The bucket 15 comprises a container of any desired shape or size. The bucket 15 is pivotally 25 supported by a bifurcated bracket 60 depending from the bogie 14. The end 22 of the cable 20 is attached to a lug 62 at one end of the bucket 15. Consequently, if the end 22 of the cable 20 is pulled upwardly, the lug 22 will also be pulled 30 upwardly and tilt the bucket 15 about the pivotal support of the bracket 60. The other end of the bucket 15 comprises a tail 65 and two side extensions 66 fixed to the tail 65. The tail 65 and the side extensions 66 are pivoted with respect to the 35 body of the bucket 15 by means of two or more curved hinges 68. Two links 70 are pivoted to the sides of the bucket 15 adjacent the lug 62, and are connected to the bifurcated bracket 60 by means of two links 71 and a horizontal rod 72. 40 The other ends of the links 70 are connected to the top of the tail 65 by means of a pair of links 74.

In operation of the conveyor system, the bucket 15 is loaded with feed or other desired materials to be transported. The bucket 15 is normally in a closed position, as shown in Figure 1 of the drawings. Rotation of the crank 40 will move the conveyor bucket 15 along the track 13 to any desired location. If the system is used in a barn, the track 13 may be marked with a plurality of indicia indicating particular stalls or animals. If desired these indicia may be colored to be more readily visible from a distance. It is understood, of course, that there may be as many stations along the track 13 as is desired, and that the 55 operator will stand at the wall 11 and turn the

crank 40 to move the bucket 15 anywhere along the track 13. Or, the cable itself may be marked.

When the bucket 15 has reached its desired location, the operator depresses either the arm 52 or the foot pedal 54. This will move up the rod 50, thereby elevating the movable pulley 31. The movement of the pulley 31 will exert a tension on the end 22 of the cable 20. The lug 62 will be moved upwardly, tilting the bucket 15 clockwise. The bracket 60 depending from the bogie 14 will remain vertical, and by virtue of the connecting link 71 the link 70 pivoted on the bucket 15 will transmit motion through the link 72 to move the tail 65 clockwise, as indicated in Figure 4, to dump the material. As soon as the required amount of material has been dumped at the desired location, the operator will release the arm 52 or the foot pedal 54, thereby restoring the bucket 15 to its closed horizontal position. The bucket 15 can then be manipulated to another station and the dumping operation repeated.

What is claimed is:

1. In a conveyor system comprising an overhead track, fixed supports therefor, a bogie movable on the track and a bucket suspended from the bogie, an end gate pivoted at the lower end thereof to the forward end of the bucket to form a closure therefor, a pair of corresponding rotatable pulleys individually mounted on the supports, and a cable mounted over the two pulleys, improvement which includes means upon the forward end of the bogie connected to one end of the cable, a pulley rotatably mounted on the rear end of said bogie, a manually rotated pulley pivotally mounted on one fixed support, with the other end of the cable extending from the last mentioned pulley down about the manually rotated pulley and extending to and over the pulley on the rear end of said bogie and finally down to and secured to the rear end of said bucket, the suspension of the bucket on said bogie including a pivotal mounting rockably supporting said bucket intermediate the ends thereof, and manually rotated tensioning means for lengthening the section of the cable extending between the manually operated pulley and the pulley upon the rear end of said bogie by applying tension thereto whereby to elevate the rear end of said bucket and tilt the latter.

2. In a conveyor system comprising an overhead track, fixed supports therefor, a bogie movable on the track and a bucket suspended from the bogie, an end gate pivoted at the lower end thereof to the forward end of the bucket to form a closure therefor, a pair of corresponding rotatable pulleys individually mounted on the supports, and a cable mounted over the two pulleys, improvement which includes means upon the forward end of the bogie connected to one end of the cable, a pulley rotatably mounted on the rear end of said bogie, a manually rotated pulley pivotally mounted on one fixed support, the further pulley rotatably mounted on the latter fixed support intermediate one of the first mentioned pulleys and the manually rotated pulley with the other end of the cable extending from said one of the first mentioned two pulleys down about the manually rotated pulley and extending up over the further pulley and thence to and over the pulley on the rear end of said bogie and finally down to and secured to the rear end of said bucket, the suspension of the bucket on said bogie including a rigid depending bracket terminating at the lower end thereof in a pivotal

mounting rockably supporting said bucket intermediate the ends thereof, and manually operated tension means for lengthening the section of the cable extending between the further pulley and the pulley upon the rear end of said bogie by applying tension thereto and thereby elevating the rear end of said bucket to tilt the latter.

3. In a conveyor system comprising an overhead track, fixed supports therefor, a bogie movable on the track and a bucket suspended from the bogie, an end gate pivoted at the lower end thereof to the forward end of the bucket to form a closure therefor, a pair of corresponding rotatable pulleys individually mounted on the supports, and a cable mounted over the two pulleys, improvement which includes means upon the forward end of the bogie connected to one end of the cable, a pulley rotatably mounted on the rear end of said bogie, a manually rotated pulley pivotally mounted on one fixed support, the further pulley rotatably mounted on the latter fixed support intermediate one of the first mentioned pulleys and the manually rotated pulley with the other end of the cable extending from said one of the first mentioned two pulleys down about the manually rotated pulley and extending up over the further pulley and thence to and over the pulley on the rear end of said bogie and finally down to and secured to the rear end of said bucket, the suspension of the bucket on said bogie including a rigid depending bracket terminating at the lower end thereof in a pivotal mounting rockably supporting said bucket intermediate the ends thereof, and manually operated tension means for lengthening the section of the cable extending between the further pulley and the pulley upon the rear end of said bogie by applying tension thereto and thereby elevating the rear end of said bucket to tilt the latter, said manually operated tensioning means including a pulley support movably mounted upon one fixed support, a pulley rotatably mounted on said pulley support in active engagement with said cable intermediate said manually rotated pulley and said pulley on the bucket, and a lever pivoted at an intermediate portion thereof on the last mentioned one fixed support with one end of said lever pivotally connected to said pulley support to move the latter at will.

4. In a conveyor system comprising an overhead track, fixed supports therefor, a bogie movable on the track and a bucket suspended from the bogie, an end gate pivoted at the lower end thereof to the forward end of the bucket to form a closure therefor, a pair of corresponding rotatable pulleys individually mounted on the supports, and a cable mounted over the two pulleys, improvement which includes means upon the forward end of the bogie connected to one end of the cable, a pulley rotatably mounted on the rear end of said bogie, a manually rotated pulley pivotally mounted on one fixed support, the further pulley rotatably mounted on the latter fixed support intermediate one of the first mentioned pulleys and the manually rotated pulley with the other end of the cable extending from said one of the first mentioned two pulleys down about the manually rotated pulley and extending up over the further pulley and thence to and over the pulley on the rear end of said bogie and finally down to and secured to the rear end of said bucket, the suspension of the bucket on said bogie including a rigid depending bracket terminating at the lower end thereof in a pivotal

mounting rockably supporting said bucket intermediate the ends thereof, and manually operated tension means for lengthening the section of the cable extending between the further pulley and the pulley upon the rear end of said bogie by applying tension thereto and thereby elevating the rear end of said bucket to tilt the latter, said manually operating tensioning means including a vertically movable elongated pulley support, a guide rigidly mounted on said one fixed support for guiding the elongated pulley support in vertical sliding movement, a pulley on the latter held thereby against said cable intermediate said manually rotated pulley and said pulley on the bucket, and a lever pivoted at an intermediate portion thereof on the last mentioned one fixed support with one end pivoted to said elongated pulley support to slide the latter in said guide at will.

5. In a conveyor system comprising an overhead track, fixed supports therefor, a bogie movable on the track and a bucket suspended from the bogie, an end gate pivoted at the lower end thereof to the forward end of the bucket to form a closure therefor, a pair of corresponding rotatable pulleys individually mounted on the supports, and a cable mounted over the two pulleys, improvement which includes means upon the forward end of the bogie connected to one end of the cable, a pulley rotatably mounted on the rear end of said bogie, a manually rotated pulley pivotally mounted on one fixed support, with the other end of the cable extending from the last mentioned pulley down about the manually rotated pulley and extending to and over the pulley on the rear end of said bogie and finally down to and secured to the rear end of said bucket, the suspension of the bucket on said

- bogie including a rigidly depending bracket terminating at the lower end thereof in a pivotal mounting rockably supporting said bucket intermediate the ends thereof, a first class lever pivotally mounted upon said bucket rearwardly of the pivotal mounting of the depending bracket, a link connecting one end of said first class lever with an intermediate portion of said depending bracket to a given distance above said pivotal mounting thereof, there being pivot connections at both ends of said link, and the second link pivotally connected to the other end of said first class lever and to the upper end of said gate on the forward end of said bucket, and operable tension means for lengthening the section of the cable extending between the further pulley and the pulley upon the rear end of said bogie by applying tension thereto in order to elevate the rear end of said bucket and simultaneously cause operation of said first class lever and links and thereby open said end gate upon the bucket while tilting the latter.
